FOREIGN PATENT DOCUMENTS

EM 001282206-0001 * 5/2011

Primary Examiner — Marie D. Fast Horse*(74) Attorney, Agent, or Firm* — McClure, Qualey & Rodack, LLP(57) **CLAIM**

The ornamental design for a wireless access point device, as shown and described.

DESCRIPTION

FIG. 1 is a front, right and top perspective view of a wireless access point device, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear, left and bottom perspective view thereof.

1 Claim, 6 Drawing Sheets(56)
